UNITED STATES PATENT OFFICE.

EMANUEL FOLGMAN, OF BROOKLYN, NEW YORK.

TORCH.

Application filed November 14, 1923. Serial No. 674,739.

To all whom it may concern:

Be it known that I, EMANUEL FOLGMAN, a citizen of the United States, and a resident of the city of New York, borough of Brooklyn, in the county of Kings and State of New York, have invented a new and Improved Torch, of which the following is a full, clear, and exact description.

The present invention relates to new and useful improvements in torches, and it pertains more particularly to torches of the self-blown type.

Great difficulty has heretofore been experienced in torches of this type with a clogging or choking up of the gas or burner tube. A further disadvantage of this type of torch is the failure to properly function of the part of the vent tube which relieves the pressure from the fuel tank after the torch has been extinguished.

It is one of the primary objects of the invention to provide a torch in which the gas or burner tube may be readily cleaned.

It is a further object of the invention to provide a vent tube of a new and improved type which will assure proper relief of the gases generated in the fuel chamber immediately after the torch has been extinguished.

It is a still further object of the invention to combine the gas tube and the vent tube in a single element, the vent tube forming a means for conveying loosened particles of any kind from the gas tube to the fuel tank or reservoir.

With the above and other objects in view, reference is had to the accompanying drawings, in which—

Figure 1 is a fragmentary view in front elevation of a torch constructed in accordance with the present invention;

Fig. 2 is a fragmentary sectional view thereof;

Fig. 3 is a fragmentary view in front elevation of a slightly modified form of the invention;

Fig. 4 is a fragmentary sectional view of the type of torch shown in Fig. 3.

Referring again to the drawings and more particularly to Figs. 1 and 2, the reference numeral 5 designates the body of the torch, and as more clearly shown in Fig. 2, this body constitutes a reservoir for fuel 6, the fuel being of a liquid type and introduced into the body 5 through the medium of the opening closed by the plug 7. The reference numeral 8 designates a tube extending

through the top wall 9 of the torch, and such tube carries a wick 10 and serves as a retort in a manner to be hereinafter described. This tube is provided with a vent 11 which extends throughout the length of the tube 8.

Projecting upwardly from the top wall 9 of the body 5, there are two curved tubes 12, and carried by each of the tubes there is a wick 13. The outer ends of the tubes 12 are preferably hexagonal in shape, as designated by the reference numeral 14, and screws, or the like, 15 are carried by each of these hexagonal ends, the screws 15 being in alinement with each other. These screws when removed leave openings for the introduction of a suitable tool for cleaning the chamber at the end of each tube 12, and in which the gas is formed.

Mounted preferably between the tubes 12 and on the exterior thereof, there is a tube 16. This tube 16 has its outer end closed by means of a screw 17 and its inner end projects through the top wall 9 of the body 5 of the torch, as indicated by the reference numeral 18. Intermediate of its ends this tube is provided with an opening 19, such opening being positioned slightly above the top of the tube 8 and formed in the tube 16 in such a manner as to project gases directly across the top of the wick 10 carried in the tube 8. The outer end of the tube 16, when it lies between the hexagonal ends 14 of the tubes 12, is provided with diametrically opposed openings 21, and such openings are adapted to provide communication between the chamber formed in the end of each tube 12 and the tube 16.

The device functions in the following manner:

To start the torch the wick 10 is lighted and the flame thereof passes upwardly into engagement with the tubes 12. As the tubes 12 are heated, the liquid fuel carried by the wicks 13 thereof is converted into gas and passes through the openings 21 in the tube 16 to the interior of the tube. From this point the gas passes down the tube 16 to the opening 19 and is projected across through the flame of the wick 10 where it is ignited. Due to the pressure under which this gas is discharged, the torch blows and continues to operate during the period which the wick 10 is ignited until the fuel is exhausted.

During the operation of the torch, a certain pressure is generated in the body 5 above the level of the fuel contained therein, and

immediately upon extinguishing the torch this pressure passes upwardly through the tube 16 and outwardly through the opening 19, thus relieving this pressure and preventing the pressure forcing liquid fuel through the wicks 13 and out through the tube 16.

It is well known that certain deposits form in the tube 16 and upon jarring the torch these deposits are dislodged causing in previous types of torches, a clogging of the tube 16. In the present device, however, the dislodged particles are moved through the tube by the passage of gas therethrough, and under the influence of gravity, the particles fall into the reservoir formed by the body 5, thus preventing a stoppage in the tube 16. This action is facilitated by the fact that the tube 16 is free from sharp bends or turns and the passage therethrough is practically uninterrupted.

In that form of the invention shown in Figs. 3 and 4, the improvement is shown as applied to a torch of the single tube type, and in this form of torch a gas tube 30 is positioned preferably beneath the wick tube 31, and such wick tube 31 is provided with a passage 32 which leads from the chamber at the outer end 33 of the wick tube into the gas tube 30. The gas tube 30 is provided with an opening 34 in proximity to the upper end of the wick tube 35 in order that gas in the gas tube 30 may be projected across the upper end of the tube 35. The tube 35 carries a wick 36 and is provided with a vent tube 37 of practically the same form as that shown in the preferred type. In this form of the invention the gas tube 30 projects below the upper wall 9 of the body 5, as designated by the reference numeral 37', and the operation is the same as in the preferred form of the invention. The wick tube 31 in this form of the invention is provided with an opening 39 closed by a screw, or the like,

40, and such opening is diametrically opposed with respect to the passage 32 in order that a cleaning tool may be inserted through the opening 39 and the passage 32. The gas tube has its outer end closed by means of a screw 41, which when removed permits of the insertion of a cleaning tool to the gas tube 30.

From the foregoing it is apparent that the present invention provides a new and improved torch in which the passages may be readily cleaned and in which the passages are of such shape and construction that the lodging of particles and a resultant clogging of the passages, is obviated.

What is claimed is:

1. In a self-blown torch, a retort chamber, a body portion forming a fuel reservoir, and a tube extending from the retort chamber to the reservoir and provided intermediate of its ends with a gas discharging opening, said tube constituting means for discharging gas formed in the retort chamber and discharging gas formed in the reservoir.

2. In a self-blown torch, a retort chamber, a gas tube leading therefrom and extending into the body of the torch, said gas tube having an unrestricted passage and a gas discharge opening intermediate of its ends.

3. In a blow torch, a fuel reservoir, a wick tube including a retort chamber and a vent tube for said reservoir, said vent tube being disposed exteriorly of the wick tube and having communication with the retort chamber.

4. In a blow torch, a fuel reservoir, a wick tube including a retort chamber and a vent tube for said reservoir, said vent tube being disposed exteriorly of the wick tube whereby clogging of the vent tube by the wick contained in the wick tube is prevented.

EMANUEL FOLGMAN.
